(57) **CLAIM**

The ornamental design for an oral device, as shown and described.

DESCRIPTION

FIG. 1 is a top perspective view of the oral device;
FIG. 2 is a bottom perspective view of the oral device of FIG. 1;

FIG. 3 is a side view for which the other side view is the same of the oral device of FIG. 1;

FIG. 4 is a front view of the oral device FIG. 1;

FIG. 5 is a rear view of the oral device of FIG. 1;

FIG. 6 is a bottom plan view from below of the oral device of FIG. 1; and,

FIG. 7 is a top plan view from above of the oral device of FIG. 1.

The broken line showing in the figures is included for the purpose of illustrating portions of the oral device and forms no part of the claimed design.
